UNITED STATES PATENT OFFICE.

LUCIUS FREEMAN LITTLE, OF OWENSBORO, KENTUCKY, ASSIGNOR TO THE ANGLO-AMERICAN MILL CO., OF OWENSBORO, KENTUCKY, A CORPORATION OF KENTUCKY.

FEED-REGULATOR FOR MILLS.

1,161,488.

Specification of Letters Patent. Patented Nov. 23, 1915.

Application filed March 1, 1915. Serial No. 11,269.

To all whom it may concern:

Be it known that I, LUCIUS FREEMAN LITTLE, a citizen of the United States, residing at Owensboro, in the county of 5 Daviess and State of Kentucky, have invented new and useful Improvements in Feed-Regulators for Mills, of which the following is a specification.

The present invention relates to feed regulators for mills, and has for its object to provide feeding mechanism which will prevent the flooding and choking of the mill in event of its being stopped, so that danger of filling the break rolls with an overflow 10 of grain when the mill is not in operation is entirely done away with, and an even and normal distribution of grain will be maintained while the mill is running, and choking of the rolls during stoppage of the mill 15 is eliminated.

I have illustrated my invention in connection with a well known type of roller mill, in which the grain to be reduced is fed from a suitable hopper to the break rolls, and 20 thence, as is usual, to suitable bolting and reducing instrumentalities.

In the drawings accompanying and forming part of this specification, I have illustrated only so much of a conventional mill as 25 is necessary to an understanding of my invention, and in said drawings—

Figure 1 is a side elevation of a portion of a mill with my feed mechanism attached thereto. Fig. 2 is an enlarged plan view of 30 the feed mechanism which I have invented. Fig. 3 is an enlarged front view of the feed mechanism shown in the other views.

Referring to the drawings by numbers, like numbers indicating like parts in the 35 several views, 10 indicates a mill of any suitable type having a hopper at its top from which the grain is fed to the reducing instrumentalities within the mill casing.

Mounted in the mill is the feed board 11, 40 which comprises the feed pocket 12, and the inclined feed board 13 which delivers to the break, conventionally shown. The said feed board 11 is oscillated by any suitable mechanism, as for example the eccentric 14 and 45 thrust rod 15, so as to agitate the contents of the feed pocket 12, and cause it to flow in a regular stream over the inclined board or screen 13, as is not unusual in this type 50 of mill. The said feed board 11 is provided 55 with a pair of bracket arms 16 projecting

upwardly therefrom, and securely fastened at their lower ends by means of suitable fastening means, such as bolts and nuts 17, so that the said bracket arms partake of the motion of the feed board as it is oscillated by the mechanism just described. Mounted upon the said bracket arms 16 is a regulator board or feed-controlling plate 18, this board being slightly inclined with its delivery end overhanging the feed pocket 12, 60 the said regulator board being closed at its back and sides, as shown in Fig. 1, and preferably it will be adjustably mounted by means of the bolts 19 adjustable in slots 20 formed in the bracket arms 16. The said 65 regulator board is mounted just beneath the feed hopper 21, which may be of any suitable design, and the lower end of which will be in proper feeding relation to the board 18, so that the stream of grain will readily flow 70 from the hopper 21 onto the regulator board 18, and thence fall to the feed pocket 12, from which it will flow down the feed board 13 to the mill.

It will be obvious that as the feed board 75 11 is oscillated the feed regulator board 18 will partake of those oscillations, and the stream of grain from the hopper being constantly agitated will flow readily and keep up a continuous delivery of the grain to the 80 mill. Immediately the operation of the mill is stopped however the feed regulator 18 will come to a state of rest, and the stream of grain flowing from the hopper will be no longer agitated, but immediately the board 85 18 comes to a state of rest the grain will be choked back and its flow discontinued, the excess of flow simply spreading over the board 18 to a slight extent without any undue loading of the feed pocket 12, and a 90 consequent excess on the board or screen 13 or objectionable flow from said board 13 to the reduction rolls. Immediately the mill starts the board 18 will begin to deliver to the feed pocket 12, and the flow from the 95 hopper 21 will be resumed.

The regulator board 18, it will be observed, is adjustable both vertically with respect to the hopper and angularly by means of the bolts 19 and slots 20, so that a greater 100 or less inclination may be given to it to secure the proper angle to insure the choking back of the grain in the hopper and avoidance of the flooding of the main feed board upon stoppage of the mill, the area 105 110

of the board 18 being figured out so as to give a sufficient capacity to take care of the flow from the hopper, and secure the proper choking back of the grain.

5. By means of this supplemental regulator board in conjunction with the ordinary feed board I am enabled to very effectively control the flow of grain from the hopper and maintain always a normal condition of the 10 grain in the feed pocket 12, and on the main feed board 13, so that there is no likelihood of flooding the mill during stoppage, nor is the regular feed board loaded to excess so that upon starting an abnormal quantity 15 of grain is delivered to the reduction rolls.

It will be understood that structural departures may be made from the apparatus here shown, and I do not, therefore, limit myself to the particular embodiment of my 20 invention herein set forth.

I claim:—

1. In a mill, the combination with a feed-hopper, of a feed-board, means for oscillating said board, and an oscillating feed-controlling plate between said hopper and said feed-board, said plate being vertically and angularly adjustable in relation to said hopper. 25
2. In a mill, the combination with a feed-hopper, of a feed-board, means for oscillating said board, rigid bracket arms extending upwardly therefrom, and a feed-controlling plate mounted on said arms between said board and hopper to control the flow from 30

the hopper and insure a regular feed to said 35 board and the mill, and means for adjusting said feed-controlling plate both vertically and angularly relative to said hopper.

3. In a mill, the combination with a feed-hopper, of a feed-board, means for oscillating 40 said board, rigid bracket arms extending upwardly therefrom, and a feed-controlling plate mounted for vertical and angular adjustment on said arms between said board and hopper to control the flow from the 45 hopper and insure a regular feed to said board and the mill.

4. In a mill, the combination with a feed-hopper, of a feed-board comprising a feed-pocket and an inclined portion, means for 50 oscillating said feed-board, rigid bracket arms extending upwardly therefrom, a feed-controlling plate mounted on said arms between said hopper and said feed-board and having its delivery end overhanging the 55 feed-pocket of said feed-board, and means for mounting said feed-controlling plate on said arm and for adjusting said feed-controlling plate both vertically and angularly relative to said hopper. 60

In testimony whereof I have hereunto set my hand in presence of two subscribing witnesses.

LUCIUS FREEMAN LITTLE.
